UNITED STATES PATENT OFFICE.

FRED MCRAE BAWDEN, OF TORONTO, ONTARIO, CANADA.

TURRET.

1,272,188.

Specification of Letters Patent.

Patented July 9, 1918.

Application filed January 26, 1918. Serial No. 214,019.

To all whom it may concern:

Be it known that I, FRED MCRAE BAWDEN, a subject of the King of Great Britain, residing in the city of Toronto, county of 5 York, Province of Ontario, Canada, have invented certain new and useful Improvements in Turrets, of which the following is a specification.

My invention relates to improvements in 10 turrets, and the objects of my invention are: first, to produce a horizontal revolving turret provided with a plurality of bars which support the cutters firmly so that true deep borings may be made and whereby consecutive operations may be carried out without 15 loss of time and impairment in accuracy of work; second, to provide a convenient support for the boring-barrel carrying the bars, so that this barrel may be readily manipulated and locked in position, and so that the cutter in operation will be rigidly held with 20 the longitudinal center of its supporting bar in alinement with the longitudinal center of the lathe-spindle; third, to provide suitable 25 indexing-means whereby the desired cutter can be readily located in working position prior to locking, and fourth, to provide suitable means for moving the boring-barrel to change the cutters.

The preferred form of my invention and a suitable mounting therefor will be herein-after particularly set forth, and what I claim as new will be pointed out in the claims forming part of this specification.

Figure 1 is a side elevation of my turret showing the same movably mounted on a machine bed, part of which is shown in side elevation. Fig. 2 is an end elevation of my turret showing particularly the indexing and moving and locking means for the boring-barrel. This view also shows an end elevation of a suitable machine-bed supporting the turret. Fig. 3 is an end elevation of mounting means for the boring-barrel, and 40 Fig. 4 is a side elevation thereof; Fig. 5 is a side elevation of the boring-barrel, a portion of one plate being shown in section, and Figs. 6 and 7 are end elevations of the boring-barrel.

In the drawings, like characters of reference refer to the same parts.

It is well-known that in making many deep borings, particularly in connection with the manufacture of shells, it is absolutely necessary that the walls of the bore be ab-

solutely free of any inequalities of surface, otherwise, especially in this particular class of work, the product will be useless. Now to provide a bore of positive uniform diameter throughout its length, and so absolutely overcome the disadvantages experienced with this class of machine now on the market, particularly in connection with the manufacture of shells, I have provided the 60 turret I shall now particularly describe in its preferred form. From the results of the machine in actual daily use, it has been abundantly proven that I have succeeded in attaining the object in view.

My turret comprises a boring-barrel A, the 70 preferred form of which comprises end circular plates B and C, connected together by a hub D. The said plates together with the said hub are preferably cored to reduce weight, and without sacrificing strength. 75 The said boring-barrel is mounted to horizontally rotate within the split standards E and E', which are carried by any suitable support F, which in the preferred form of invention is in the form of a carriage which 80 is mounted to move longitudinally on any suitable machine bed G. The plate B is journaled in the standard E, whereas the plate C is journaled in the standard E'. Each of these standards is provided at one 85 side only with a pair of lugs H, spaced apart as shown very clearly in Fig. 3, and supported by said lugs in order to lock or release the boring-barrel by any suitable means. The preferred means employed for this purpose 90 comprises a bar 2 passing through holes 3 formed in said lugs. Pivoted by a pin 4 in the lower end of each of these bars, is a lever 5 having its upper end preferably bifurcated as shown at 6. The outer portions 95 7 of the bifurcated end 6, of each lever 5, is eccentric to the pin 4, and when the said levers are in the position illustrated in Figs. 1 and 2, they co-act with the adjusting nuts 8, screwed on the upper threaded end of each bar 2 so as to grip the plates B and C in their respective standards in order to positively lock the boring-barrel in adjusted 100 position.

A plurality of bars 9 are mounted in 105 alined holes 10 formed in the plates B and C, and the said bars are suitably locked in place. Each bar 9 is of course provided with a suitable cutter.

10' represents the chuck, and the axis of 110

rotation of the same is that of the spindle (not shown) and this axis of rotation is represented by the line 11. It will be observed that the line 11 passes centrally longitudinally through the bar 12; it therefore follows that the bar in the position just identified is the one that supports the working cutter.

The boring-barrel together with its bars, 10 is very heavy, and some means must be used to readily move the same so as to position the required cutter. My preferred means for this purpose comprises a ratchet plate 13, secured by any suitable means such as 15 screws 14 to the outer face of the plate C of the boring-barrel A. 15 is a lever mounted on the stud 16, which stud is held in the ratchet plate. A pawl 17 is pivoted to the lever 15, and co-acts with the ratchet plate 20 13 to permit the boring-barrel A to be moved.

Mounted in the ratchet-plate 13 are a plurality of bushings 18, preferably tapered, and the axes of these bushings are so located 25 that when the locating pin 19 is moved thereinto, the cutter bar carrying the cutter to do work, will be absolutely positioned with its longitudinal axis in alignment with the axis of the spindle. The end 20 of the 30 pin 19 is tapered so as to facilitate entry thereof into the bushings 18. The pin 19 is threaded in the bracket 21, and is preferably provided with a hand-wheel 22 for ease and speed of manipulation.

35 It will of course be understood that the boring-barrel A must be unlocked to permit of the movement thereof, and prior to this movement, the locking pin 19 must be withdrawn from its bushing. After proper location of the desired bar 9, the boring-barrel 40 is then firmly locked.

To prevent longitudinal displacement of the boring-barrel, any suitable construction may be employed. In order to provide a 45 very simple means for this purpose, I provide the plate B with an annular peripheral flange 23 which is housed within the annular groove 24 formed in one side of the standard E. The ratchet plate 13 is of greater diameter than the plate C, and therefore since this ratchet plate operates against the outer face of the standard E', it will be clear that said boring-barrel will not be longitudinally displaced.

55 While any desired number of bars 9 may be used, I prefer to use three, because thereby I mount in the one boring-barrel the necessary number of cutters required, and at the same time secure the maximum distance 60 between the bars 9 to prevent the same coming in contact with the head of the lathe.

The bars 9 are made very strong, and while they have considerable overhang in respect of the boring-barrel A, still by reason of the fact that they are given very firm

support in the said boring-barrel, there will be no undesirable movement in the cutters.

My turret embraces the single-bar idea with its rigidity, with the added advantage of a plurality of bars possessing the same rigidity and immediately available for use in respect of consecutive operations, this saving much time and trouble, and insuring accuracy in work.

I find that the use of three cutter-bars spaced substantially one hundred and twenty degrees apart, and of course with their longitudinal axes at the same distance from the center of rotation of the rotary member supporting the same, gives me ample room between the bars so that particularly in respect of the boring of shells, I am enabled to have the desired clearance for the handling of the work without the necessity of having to move the carriage as far away from the chuck as would be necessary if the cutter-bars were not grouped as stated; this is an important feature of my invention.

While I have described what I consider to be the best embodiment of my invention, I desire it to be understood that the principle may be embodied in many different forms within the terms of my claims and yet avoid the prior art.

Claims:

1. A turret comprising a rotary member provided with a plurality of horizontal holes therethrough to receive cutter-bars; bearing-locking means in which said member is mounted to rotate on a horizontal axis, and whereby said member is locked, and an indexing-device whereby the cutter carried by said member to be put to work is readily accurately located prior to the locking of said member.

2. A turret comprising a rotary member provided with a plurality of horizontal holes therethrough to receive cutter-bars; a pair of split standards, spaced apart, in which the said rotary member is mounted to rotate on a horizontal axis; an indexing-device whereby the cutter carried by said member to be put to work is readily accurately located, and means whereby said rotary member is locked in said standards subsequent to the use of said indexing means.

3. A turret comprising a rotary member provided with a plurality of horizontal holes therethrough to receive cutter-bars; a pair of split standards, spaced apart, in which said rotary member is mounted to rotate on a horizontal axis; the said standards being each provided with a pair of lugs at their split sides; an indexing-device whereby the cutter carried by said member to be put to work is readily accurately located, and means carried by the said pairs of lugs whereby said rotary member is locked in said standards subsequent to the use of said indexing-means.

4. A turret comprising a rotary member provided with a plurality of horizontal holes therethrough to receive cutter-bars; a pair of split standards spaced apart in 5 which the said rotary member is mounted to rotate on a horizontal axis; an indexing-device comprising a ratchet-plate secured to one end of said rotary member adjacent the outer side of one of said standards, and provided with a plurality of holes suitably located corresponding to the number of cutter-bars carried by said rotary member; a locating pin; a bracket in which said locating pin is mounted to operate; the said locating-pin co-acting with the holes in said indexing-plate for the purpose specified; a lever pivoted to said ratchet-plate; a pawl pivoted to said lever and co-acting with said ratchet-plate to turn said rotary member, 15 and means carried by each of the said split 20

standards whereby said rotary member is locked therein.

5. A turret comprising a boring-barrel formed of a hub provided at each end with a 25 plate, one of said plates being provided at its outer edge with an annular peripheral flange, the said plates being provided with a plurality of alined holes; a pair of standards spaced apart carried by a suitable support, one of said standards being provided with an annular groove in which operates the peripheral flange carried by one of said plates since the said plates are designed to be mounted in said standards so as to operate on a horizontal axis, and means attached 30 to one of said plates and operating against the outer side of its associated standard to prevent longitudinal displacement of said boring-barrel. 35

FRED McRAE BAWDEN.
